UNITED STATES PATENT OFFICE.

MICHAEL FLYNN AND MICHAEL J. BUCKLEY, OF PITTSTON, PENNSYLVANIA.

DESIGN FOR A TOOTH FOR ORE-BREAKERS.

SPECIFICATION forming part of Design No. 24,269, dated April 30, 1895.

Application filed December 31, 1894. Serial No. 533,475. Term of patent 7 years.

To all whom it may concern:

Be it known that we, MICHAEL FLYNN and MICHAEL J. BUCKLEY, citizens of the United States, residing at Pittston, in the county of Luzerne, State of Pennsylvania, have invented and produced a new and original Design for a Tooth for Ore-Breakers, of which the following is a specification, reference being had to the accompanying drawings, showing a part thereof.

Figure 1 is an elevation of the tooth detached. Fig. 2 is a top plan view thereof. Fig. 3 is a cross-section on line $x-x$, Fig. 1. Fig. 4 is a cross-section on line $y-y$, Fig. 1, these four drawings being deemed necessary to illustrate our design.

The leading feature of our design consists in a tooth having a cylindrical body, increased in size at its upper end and slotted transversely and terminating in a point at its lower end, rectangular in cross section.

—A— is the body of the tooth; —a—, the

upper end increased in size as shown, having a transverse slot-way —a'—.

—b— is the lower end rectangular in cross section and terminating in the point —b'—.

The regular circular outline of the upper portion of the body combined with the rectangular lower end of the body, presents to the eye the combined effect of a smooth circular outline and rectangular point.

Having described our invention, what we claim, and desire to secure by Letters Patent, is—

The design for a tooth for ore breakers, substantially as described and shown.

In witness whereof we have hereunto set our hands on this 28th day of September, 1894.

MICHAEL FLYNN.
MICHAEL J. BUCKLEY.
